UNITED STATES PATENT OFFICE.

ALVAH H. McCLEARY, OF DETROIT, MICHIGAN.

SHACKLE FOR SPRINGS.

1,326,757.

Specification of Letters Patent. Patented Dec. 30, 1919.

Application filed July 24, 1918. Serial No. 246,530.

To all whom it may concern:

Be it known that I, ALVAH H. McCLEARY, a citizen of the United States of America, residing at Detroit, in the county of Wayne 5 and State of Michigan, have invented new and useful Improvements in Shackles for Springs, of which the following is a specification.

As its principal object, the invention 10 seeks the provision of a device of the above mentioned character particularly adapted for heavy duty motor trucks and the like, the device being a shackle in which a large bearing surface is presented to the spring 15 with which it is connected and this bearing surface being provided with means reducing to a minimum the friction and wear. The shackle is of such a character and of such construction that it may be easily attached to or removed from a spring with 20 which it is used, unique retaining means being provided to secure the shackle to the spring when mounted thereon. This retaining means is removable for the purpose of 25 permitting the shackle to be removed from the spring.

It is customary in spring shackles to have the top of the shackle supported on thin edges. These edges soon wear from continued friction and effect great wear on the 30 spring shackle and it is one of the purposes of this invention to avoid this disadvantage.

The invention is illustrated and described in a specific embodiment to which, however, 35 it is not to be restricted. The right is reserved to vary the details of construction in any manner compatible with the spirit of the subjoined claim.

In the accompanying drawings:

Figure 1 is a section in side elevation of 40 the shackle spring with the improved shackles attached thereto.

Fig. 2 is a view partly in section and partly in elevation of the shackle *per se*.

Fig. 3 is a view similar to Fig. 2 but looking from a direction at right angles to the latter.

Referring to the drawings, there is shown a conventional form of leaf spring 1, such 45 as would be attached to the running gear of a vehicle, or heavy duty motor truck with which the invention is particularly designed for use. The uppermost leaf of the spring 1 is formed at its extremities with

upturned lips or flanges 2 and the improved 55 shackles engage the spring on this uppermost leaf adjacent these lips.

The shackle is in the form of an open frame member formed with the cylindrical portion 3, the two leg portions 4 and the 60 top or cap portion 5. All of these parts are integrally connected and the frame is made in any acceptable manner, preferably by drop forging, or by casting in steel. The 65 cap or top portion 5 is formed with the depending flanges 6 connecting at either end with the legs 4. Thus there is provided a depression on the underface of the cap portion 5 designed to receive the rollers 7 which 70 are of the length equal to the distance between the two arms 4 and of a diameter slightly greater than the height of the flanges 6 from their free edges to their line of juncture with the underface of the cap portion 5.

When attached to the spring 1, the rollers 7 bear on the upper face of the uppermost leaf and in order that they may be retained in position and the frame itself retained in position on the spring, the two 80 legs 4 are drilled transversely for the reception of bolts 8, the heads of which abut the underface of the uppermost leaf of the spring.

When it is desired to remove the shackle, 85 the removal of the bolts 8 will permit the frame being lifted off the spring. In attaching to the spring the rollers are first placed on top of the upper leaf and the frame inserted over the said upper leaf 90 after which the cap portion 5 is allowed to rest upon the rollers, the latter being held in the depression in the underface of the cap portion 5. The attachment of the bolts 8 then prevents the removal of the 95 shackle, as it prevents the frame being raised and so long as the frame is prevented from being raised, the lips 2 serve to retain the shackles on the spring and also the rollers are retained in the depression.

The cylindrical portion 3 of the spring is bored longitudinally to receive the bolt 9 which is intended to engage brackets or other devices carried by the body or other springs for attachment to the shackle.

Substantially at its longitudinal center 105 the cylindrical portion 3 is provided with an oil hole 10 for the lubrication of the bolt 9.

The invention having been described what is claimed as new and useful is:

The combination with an auto vehicle leaf spring having an upturned lip at one end, 5 of an open frame in surrounding relation to the spring adjacent the lip, the frame being formed with a cap portion having a depression in its underface, rollers bearing upon the face of the spring and resting in

said depression, the frame being formed 10 with legs abutting the spring on the sides, and bolts secured in the legs and having their head portions abutting the spring on the face opposite that against which the aforesaid rollers bear.

In testimony whereof I affix my signature.

ALVAH H. McCLEARY.
